Patented Jan. 23, 1962

192,116

CASING FOR AN ELECTRONIC TESTING INSTRUMENT OR SIMILAR ARTICLE

Eric Allen Inholder, Menlo Park, Calif., assignor to
Hewlett-Packard Company, Palo Alto, Calif., a corporation of California

Filed Mar. 16, 1960, Ser. No. 59,766

Term of patent 14 years

(Cl. D26—5)

Fig 1

Fig 2

Fig 3

Fig 4

FIGURE 1 is a perspective view of a casing for an electronic testing instrument or similar article, showing my new design;

FIGURE 2 is a front elevational view;

FIGURE 3 is a side elevational view, the opposite side being substantially a mirror image thereof; and

FIGURE 4 is a rear elevational view thereof.
The broken line showing of legible matter in FIGURES 1 and 2 is for illustrative purposes only.

I claim:

The ornamental design for a casing for an electronic

testing instrument or similar article, as shown and described.
